UNITED STATES PATENT OFFICE.

JAMES P. SNEDDON, OF BARBERTON, OHIO, ASSIGNOR TO THE STERLING CO., OF CHICAGO, ILLINOIS, A CORPORATION OF NEW JERSEY.

FLANGING IMPLEMENT.

SPECIFICATION forming part of Letters Patent No. 767,602, dated August 16, 1904.

Original application filed February 14, 1903, Serial No. 143,352. Divided and this application filed October 7, 1903. Serial No. 176,039. (No model.)

To all whom it may concern:

Be it known that I, JAMES P. SNEDDON, a resident of Barberton, in the county of Summit and State of Ohio, have invented a new and useful Improvement in Flanging Implements; and I do hereby declare the following to be a full, clear, and exact description thereof.

My invention relates to apparatus for flanging the metal surrounding holes in the walls of wrought-metal boiler-headers or other tubular articles; and its object is to provide an implement for insertion in the tube and adapted to be forced through openings in the walls of the tube and which is so constructed as to accurately form flanges, which project at a slight angle from the perpendicular to the axis of the tube or other article being flanged.

In certain types of water-tube boilers the tubes are connected at either their front ends or both at their front and rear ends to vertical members, technically known as "headers," and which communicate at their upper ends with the steam and water drum. In marine boilers where lightness is essential these headers are formed of wrought metal. The tubes are inserted in holes through the rear walls of the headers, and corresponding holes are formed in the front walls to permit either of the cleaning of the tubes in some types of boilers or their removal in other types of boilers, such as Niclausse boilers. The walls of the headers are formed of comparatively thin plate metal, so that it is necessary to form flanges around the holes in order to provide proper seats for the water-tubes or to provide a suitable seat for the handholds which close the openings in the front walls. These flanges ordinarily are turned outwardly and are formed by inserting a suitable tool or imple-

ment into the header and forcing the same through the holes in the header-walls while the latter is supported upon a suitable bed-die or anvil which has therein a recess into which the flanges turn. In most water-tube boilers the tubes are inclined from the horizontal, and the headers generally are placed approximately in a perpendicular position, so that the flanges forming the seats for the tubes must

be inclined from the perpendicular to the axis of the header.

The object of my invention is to provide a flanging implement or projectile for use with a suitable press and whereby the flanges can be formed at the necessary incline from the perpendicular with ease and accuracy.

In the accompanying drawings, Figure 1 is a sectional elevation of a portion of a flanging-press and a header, showing my invention applied thereto; and Fig. 2 is a side view, on an enlarged scale, of one of the flanging implements.

In use preferably all of the holes in one face of the header will be simultaneously flanged, so as to do away with unnecessary re-heatings and handlings. Consequently as many implements will be used as there are holes in one of the header-walls, and said implements will be used with a gang-press having as many plungers as there are implements and having a bed-die or anvil provided with as many recesses as there are plungers. The invention has been so illustrated in the drawings.

In said drawings the anvil or supporting-die upon which the header is placed is represented at 1. This is provided with a series of holes or recesses 2 in the face thereof, said recesses in number, dimensions, and relative spacing corresponding to the number, diameter, and relative positions of the water-tubes required for the particular boiler for which the header is designed. Around the upper ends of these holes are annular recesses 3, which form, in effect, die-cavities into which the flanges are turned and by which they are shaped to some extent. Above the anvil or die 1 is a suitable support or cross-head 4, carrying a series of plungers or pins 5, corresponding in number, dimension, and relative spacing to the holes in the anvil. In order to give the flanges of the header the proper inclination to the perpendicular, the upper face of the anvil or die 1 is inclined, the particular inclination shown in the drawings being an angle of one to ten to the horizontal; but this of course will vary with different head-

ers. As a consequence when the projectiles are forced through the holes in a perpendicular direction the flanges will be given the proper inclination. The pins or plungers 5 preferably will all be of the same length, and the lower face of the support or cross-head 4 is inclined in the same direction and to the same degree as the anvil 1. The same result, however, could be secured by making the 10 lowerface of the cross-head horizontal and having pins of varying lengths. The press herein shown and described, however, is not claimed in this application, but is claimed in my application filed February 14, 1903, Serial No. 15 143,352, of which application the present is a division.

For flanging tubular articles the flanged implements or projectiles must be independent of the plungers or pins 5 in order that 20 said implements can be inserted in the header 9 or other tubular article and forced through the holes in the lower wall thereof. Various forms of such implements or projectiles may be used, such as a sphere or semisphere, as 25 shown in my patent granted February 11, 1902, No. 693,177, or a section of an ellipse, section of a cone, or any other preferred shape. A preferred form of such implement is shown in Fig. 2, the same having a body portion 10, 30 which is a modified inverted truncated cone of circular outline in horizontal section and having two of its opposite curved or flaring sides struck about different centers or about centers at different heights or otherwise, so 35 formed that corresponding portions of such opposite side faces at their lower portions are at different heights, thus forming a supporting-face 11 at the bottom of the implement which is inclined with reference to the perpendicular axis of the implement, the inclination corresponding to the angle to be given to the flanges and in the particular implement shown being at an angle of one to ten to its vertical axis. This implement has a countersunk conical or concave depression 12 in 45 its upper face, and the lower end of each plunger or pin 5 is conical or convex, so that in operation the conical end of the pin will slide down into the countersunk recesses 12 of the implement and center itself therein. As a consequence the pins will force the implements perpendicularly and centrally through the holes in the header-walls and throw out flanges uniformly all around said holes. 50

55 Preferably the flanging implement will be provided on its lower face with a teat or projection 14, adapted to fit in the hole over which the implement is placed in order to properly position the same and to initially guide said 60 implement in its downward movement. The implements are also provided in their sides with holes 15, into which can be inserted the end of a rod 16, by means of which they can be conveniently inserted in the header and 65 placed over their respective holes.

While I have shown and described my invention particularly as adapted for flanging holes in wrought-metal headers, it is to be understood that it is not limited thereto, but that it is equally as well adapted for flanging 70 holes in other tubular articles.

It is obvious that certain features of the invention are applicable to flanging holes in tubular articles which are not supported in an inclined position and that the particular form 75 of implement is of value in flanging flat plates or any other articles when supported in an inclined position equally as well as for flanging tubular headers when supported in a similar position.

80 What I claim is—

1. A flanging implement comprising a body of the form of an inverted modified truncated cone having a concave depression in its upper face adapted to center a plunger or punch. 85

2. A flanging implement comprising a body of the form of an inverted modified truncated cone having a teat or projection on its lower face and a concave depression in its upper face adapted to center a plunger or punch. 90

3. A flanging implement comprising a body of circular outline in horizontal section and having side faces flaring upwardly from its lower end, two opposite side faces having corresponding portions at the lower end of the 95 implement at different heights, thereby forming a supporting-face at the bottom of the implement which is inclined with reference to its perpendicular axis.

4. A flanging implement comprising a body 100 of circular outline in horizontal section and having side faces flaring upwardly from its lower end, two opposite side faces having corresponding portions at the lower end of the implement at different heights, thereby forming a supporting-face at the bottom of the implement which is inclined with reference to its perpendicular axis, and a teat or projection 105 on the lower face of said implement.

5. A flanging implement comprising a body 110 of circular outline in horizontal section and having side faces flaring upwardly from its lower end, two opposite side faces having corresponding portions at the lower end of the implement at different heights, thereby forming a supporting-face at the bottom of the implement which is inclined with reference to its perpendicular axis, and a punch-centering face 115 on the upper side of said implement.

6. A flanging implement comprising a body 120 of circular outline in horizontal section and having curved side faces flaring upwardly from its lower end, the opposite side faces having corresponding portions at the lower end of said implement at different heights, 125 thereby forming a supporting-face which is inclined with reference to the perpendicular axis of the implement.

7. A flanging implement comprising a body 130 of circular outline in horizontal section and

having curved side faces flaring upwardly from its lower end, two opposite side faces having corresponding portions at the lower end of the implement at different heights, 5 thereby forming a supporting-face which is inclined with reference to the perpendicular axis of the implement, and a teat or projection on the lower face of said implement.

8. A flanging implement comprising a body 10 portion of the desired shape provided with a punch-centering face on its upper side and having a hole in one side thereof adapted for the insertion of a rod by means of which the implement can be placed in a tube.

9. A flanging tool or implement comprising 15 a compact integral body of the desired shape provided with a teat or projection on its lower face, a punch-receiving face on its upper side, and having a hole in one side thereof adapted for the insertion of a rod by means of which 20 the implement can be placed in a tube.

In testimony whereof I, the said JAMES P. SNEDDON, have hereunto set my hand.

JAMES P. SNEDDON.
